UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,380,857.

Specification of Letters Patent. Patented June 7, 1921.

Application filed December 31, 1919. Serial No. 348,510.

To all whom it may concern:

Be it known that I, SAMUEL B. WILLIAMS, Jr., a citizen of the United States, residing at Brooklyn, in the county of Kings and 5 State of New York, have invented certain new and useful Improvements in Telephone-Exchange Systems, of which the following is a full, clear, concise, and exact description.

This invention relates to automatic telephone exchange systems, and more particularly to systems in which line finders are employed for establishing a connection between a calling line and an idle trunk.

In automatic telephone exchange systems 15 which employ power-driven line finders operating in conjunction with contact banks of the well-known panel type, the connection between a calling line and an idle trunk may be, in some cases, slower than is desirable, since in the switch of standard construction, the contact bank contains 500 terminal sets served by ten multiplied brushes on a common operating shaft. After a given brush has been selected, if the calling line 20 is represented in the bank by the last terminal set, it is necessary for the selected brush set to advance over fifty terminals in order to accomplish the desired connection.

It is an object of the present invention to 30 materially reduce the average time required in establishing a line to trunk connection by a novel arrangement of the grouping in the contact banks, without changing the mechanical construction of the apparatus.

35 A feature of the invention is a special subgrouping arrangement within the main group of lines served by a line finder. The resultant subgroups are then "slipped" to the various finder contact banks in such a manner that normally a shorter hunting period will be required.

40 A further feature of the invention resides in the provision of allotters individual to the various subgroups. These allotters are arranged to start finders which have access to contact banks in which the line of the originating subscriber appears as an early choice. If all the first choice finders of a given subgroup are busy, a finder which is 45 normally a first choice for the allotter of some other subgroup may be started in operation.

50 An additional feature of the invention results from an arrangement whereby the allotter switch of a subgroup, after allotting

a switch which was not among its first choice switches, will return to its normal position and allot a first choice switch in case that a first choice switch has meanwhile become available for use.

The objects and features of the invention have been described in connection with a five hundred point power-driven panel bank line finder, in order to clearly show the advantages resultant from a specific employment 60 of this invention. Since the invention is obviously capable of a variety of uses and in conjunction with a variety of types of switches, it is to be limited only by the appended claims.

70 It is thought that the invention will best be understood from the following detailed description, reference being had to the accompanying drawings.

In the drawings, Figure 1 indicates partially the circuits of two finder switches and some of the group-controlling circuits arranged in accordance with this invention. Fig. 2, which should be placed below Fig. 1, shows the circuits of two allotter switches, 75 there being an allotter switch individual to each set of subgroups of calling lines. Fig. 3 shows, diagrammatically, the general outline of the system.

80 Referring now to Fig. 3, there are shown two groups of panel-bank power-driven line finders provided with common trip magnets 85 1 and 2. The mechanical construction of these switches is similar to that shown and described in Patent No. 1,177,044, issued on March 28, 1916, to J. L. McQuarrie. Each switch includes a vertically movable brush shaft 3 carrying ten brush sets, three of which are indicated at 4, 5 and 6. When magnet 1, for instance, is operated, subsequent upward movement by a brush shaft will trip the second set of brushes into operative engagement with the contact bank served by it, which contact bank comprises a main group of fifty line terminals. In accordance with the present invention, each main group of terminals is divided into two subgroups of twenty-five lines each.

90 95 100 105 110 One group of line finders is shown as having access to the terminals on the panel bank indicated generally at A, while another group of finders is shown as having access to the panel bank indicated generally at B. Referring now to the first main group, it is to be observed that there is individual to the

first subgroup of such main group which is indicated at 7, an allotter, generally indicated at 8 which, upon moving in a clockwise direction, serves to allot, as first 5 choices, the finders having access to bank A. The subgroup 7 contains numbers from 0 to 24. Therefore, if a call is originated in subgroup 7, allotter 8 will operate to put into operation one of the finders serving 10 bank A as a first choice, and, therefore, this finder will have to travel over a number of lines not exceeding twenty-five, in order to establish the desired connection. Should a 15 line in subgroup 9 of the first-named group of one hundred lines initiate a call, an allotter 10 would put into operation one of the finders which has access to terminal bank B, provided that there is one of these finders 20 idle and available for use. It is to be observed that the lines in subgroup 9, which are numbered from 25 to 49, appear in the lower half of the first group of terminals in bank B. Therefore, if a finder serving bank B is put into operation, a maximum of 25 twenty-five steps will be all that is required to establish the desired connection.

If, at the time a subscriber at subgroup 30 7 initiates a call, all the finders which serve bank A are busy, the allotter 8 will be advanced into a position to allot a finder in group B. In this case, the finder will have to advance over the terminal sets of lines 35 25 to 49, and will then have to search for the proper line. In this case, it would be possible that the entire fifty steps would have to be taken. It is obvious that by an arrangement of this kind, it would usually be possible to establish a connection without requiring more than twenty-five steps 40 as a maximum.

Inspection of the second main group, which comprises subgroups 11 and 12, will show that the arrangement is substantially similar to that in the first-named group, that 45 is, the fifty-line group is divided into two subgroups of twenty-five lines each, and that the terminals of these lines are slipped between banks A and B in twenty-five point subgroups.

From the foregoing, it is believed that the detailed description which will now be given may be readily understood. Referring now to Fig. 1, 13 and 14 indicate substations in different subgroups of the same 55 main group of fifty lines. The controlling relays for this particular main group of fifty lines are indicated at 15, 16, 17 and 18 respectively. Relays 19, 20, 21 and 22 are individual to another main group of fifty lines. As shown, substations 13 and 14 are in the second fifty group of lines. There is provided for each succeeding main group, a set of relays common to the group and corresponding to relays 15, 16, 17 and 18. 60 65 These group relays are interconnected in a

manner which should be readily understood from the disclosure of the interconnection of the various relays in the two groups which are shown. In Fig. 2, brushes 23, 24, 25 and 26 are the brushes of an allotter controlled by a stepping magnet 27, this allotter being under the control of the second subgroup of each of the ten main groups. The allotter, comprising a stepping magnet 28 and brushes 29, 30, 31 and 32 and 70 their corresponding terminal banks, is arranged to be controlled by lines in the first subgroups of the ten main groups. The mechanical construction of the allotters is substantially similar to that of a switch 75 shown in an application, Serial No. 317,126, filed August 13, 1919, by Messrs. O. F. Forsberg and R. M. De Vigner.

Let it be assumed that the subscriber at 80 substation 13 desires to initiate a call. He will remove his receiver from the switch-hook, whereupon a circuit will be completed for line relay 33, through the armatures and back contacts of cutoff relay 34. The energization of relay 33 completes a circuit 85 from grounded battery, winding of relay 15, armature and back contact of relay 16, provided this relay is in its normal condition, conductor 35, winding of relay 36, armature and front contact of relay 33 to 90 ground. Relays 15 and 36 are energized in this circuit.

It is also to be assumed that the switch shown to the right of Fig. 1 is a switch which 100 serves terminals in bank B and that this switch is idle. It will also be assumed that the allotter controlled by magnet 27 has its brushes 23, 24, 25 and 26 in engagement with their first terminals respectively. Under 105 these assumptions, the energization of relay 15 completes a circuit from grounded battery, left-hand winding of slow-to-release relay 17, left-hand armature and front contact of relay 15, left-hand armature and back contact of relay 19, assuming this relay to 110 be deenergized, conductor 37, inner right-hand armature and back contact of relay 38, left-hand armature and back contact of relay 39, left-hand armature and back contact of relay 40 to ground. Relay 17 is energized 115 in this circuit and locks up through its right-hand winding and right-hand armature and front contact, through the right-hand armature and back contact of slow-to-release relay 21, assuming this relay to be deenergized, 120 conductor 41, winding of relay 38, left-hand armature and back contact of relay 39, left-hand armature and back contact of relay 40 to ground. Relay 38 is energized in the locking circuit of relay 17 and opens the 125 original energizing circuit of relay 17 so that no other group relays corresponding to relays 17 and 21 can be energized to start finders until the operation has progressed to a proper stage. The energization of re- 130

- lay 17 also completes a circuit for trip magnet 18 extending from grounded battery, winding of magnet 18, right-hand armature and front contact of relay 17 to ground 5 over the path described. Magnet 18 operates a common trip rod so that as soon as any finder regardless of whether it serves bank A or bank B is started, the second set of brushes on such finder will be tripped.
- 10 The energization of relay 17 also completes a circuit from grounded battery, winding of relay 42, outer right-hand armature and front contact of relay 38, conductor 43, inner left-hand armature and front contact 15 of relay 17, armature and front contact of relay 36 to ground. Relay 42 is energized in this circuit and completes a circuit from grounded battery, winding of relay 44, contact of sequence switch spring 45, conductor 20 46, allotter brush 26 and its associated contact, right-hand armature and front contact of relay 42 to ground. Relay 44 is energized in this circuit and completes a circuit from grounded battery, power magnet of sequence switch 47, lower contact of sequence switch spring 48, right-hand armature and front contact of relay 44 to ground, for moving this sequence switch out of position 1 and into position 2.
- 25 In position 2 of sequence switch 47, a circuit is completed from grounded battery, winding of up-drive magnet 49; sequence switch contact 50, right-hand armature and front contact of relay 44 to ground. Under the control of magnet 49, the brush shaft is moved upward and the second set of brushes is tripped, after which the line hunting movement takes place.
- 30 After sequence switch 47 leaves position 35 1 $\frac{1}{2}$, the original energizing circuit for test relay 44 is broken at sequence switch spring 45, but this relay remains locked up as long as test brush 51 is engaging test terminals 52 associated with busy or non-calling lines, 40 since ground will be found on these test terminals, to which it is supplied through the armatures and back contacts of the line relays associated with such lines. Due to the fact that the line relay of the calling line 45 is energized, no ground will be found on the test terminal 52 associated with the calling line, and therefore, when test brush 51 engages the test terminal of such line, this branch of the locking circuit of the relay 44 50 is opened. Relay 44 is maintained energized, however, a moment longer, due to the closure of a circuit through the upper contact of sequence switch spring 53 by way of conductor 54, commutator 55 and brush 56 to ground. When, an instant later, brush 56 55 engages an insulating segment of commutator 55, at which time the brush set will be accurately centered on the calling line terminals, the circuit of relay 44 is broken, and 60 this relay deenergizes, opening at its right-hand armature, the circuit of up-drive magnet 49 and allowing the brush set to come to rest. At its right-hand armature and back contact, relay 44 completes a circuit from grounded battery, power magnet of sequence 70 switch 47, upper contact of sequence switch spring 48, armature and back contact of relay 44 to ground for moving this sequence switch out of position 2 and into some other circuit controlling position.
- 75 The sequence switch 47, in practice, would be utilized to control the various selective operations of a district selector or some corresponding switch. Since the invention is not concerned with the operation of subsequent switches, it has not been considered necessary to show in what positions sequence switch 47 comes to rest, nor what operations take place in the various intermediate positions of such sequence switch.
- 80 It is to be observed that as soon as the line finder moves out of its normal position, commutator brush 56 engages a commutator segment 57, which is immediately above the normal position of this brush, and a circuit is completed from grounded battery, winding of relay 39, allotter brush 25 and its associated contact, conductor 58, contact of sequence switch spring 59, conductor 60, commutator segment 57, commutator brush 85 56 to ground. Relay 39 is energized in this circuit and locks up through its inner right-hand armature and front contact to ground through allotter brush 24 and its associated contact, conductor 61, upper left-hand contact of sequence switch spring 62 to ground. Relay 39 will, therefore, remain energized until test brush 24 of the allotter is brought into engagement with a terminal individual to a finder switch which is standing in position 1 and therefore idle.
- 90 After sequence switch 47 leaves position 1 $\frac{1}{2}$, the original energizing circuit for test relay 44 is broken at sequence switch spring 45, but this relay remains locked up as long as test brush 51 is engaging test terminals 52 associated with busy or non-calling lines, 95 since ground will be found on these test terminals, to which it is supplied through the armatures and back contacts of the line relays associated with such lines. Due to the fact that the line relay of the calling line is energized, no ground will be found on the test terminal 52 associated with the calling line, and therefore, when test brush 51 engages the test terminal of such line, this branch of the locking circuit of the relay 44 100 is opened. Relay 44 is maintained energized, however, a moment longer, due to the closure of a circuit through the upper contact of sequence switch spring 53 by way of conductor 54, commutator 55 and brush 56 to ground. When, an instant later, brush 56 105 engages an insulating segment of commutator 55, at which time the brush set will be accurately centered on the calling line terminals, the circuit of relay 44 is broken, and this relay deenergizes, opening at its right-hand armature, the circuit of up-drive magnet 49 and allowing the brush set to come to rest. At its right-hand armature and back contact, relay 44 completes a circuit from grounded battery, power magnet of sequence 110 switch 47, upper contact of sequence switch spring 48, armature and back contact of relay 44 to ground for moving this sequence switch out of position 2 and into some other circuit controlling position.
- 115 The energization of relay 39 completes a circuit from grounded battery, winding of stepping magnet 27, armature and back contact of magnet 27, outer right-hand armature and front contact of relay 39 to ground. Magnet 27 is energized in this circuit and continues to interrupt its own circuit until an idle finder has been found. As shown in Fig. 2, the allotter switch controlled by magnet 27 has access to three B finders as first choice, after which it has access to three A finders. The number of finders is, of course, immaterial, and if the contact banks served by the allotter brushes comprise twenty terminals, the first ten would then lead to first choice finders and the second ten would lead to second choice finders.
- 120 After the allotter brushes pass over the first three terminals, they will then start to test for an idle finder in the A group and may come to rest in a position to allot said A finder. Assuming that the A finder whose circuits are partially shown in Fig. 1, is the only one in the A group which is idle, mag-

net 27 will continue to advance the allotter brushes until brush 24 engages its sixth terminal. No ground will then be found on such sixth terminal, since lead 64 is open 5 at sequence switch contact 65 individual to such finder.

If, while the allotter is hunting over terminals associated with finders in the A group, a finder in the B group becomes idle 10 and reaches position 1, the operation of the allotter will be continued through a complete revolution and back into the B group, since, even though test brush 24 fails to find a ground when it reaches its sixth terminal, 15 relay 39 will be maintained energized by way of brush 23 through any one of the terminals associated with finders in the A group, conductor 63 which is multiplied to the lower right-hand contact of all the sequence switch spring contacts 62 associated 20 with B finders, and thence to ground at the contact of the particular sequence switch spring 62 whose associated sequence switch is in position 1. In this case, the allotter 25 will advance until such idle finder has been seized, when it will come to rest and await the initiation of another call in the second subgroup.

As soon as relay 39 was energized, due 30 to the fact that an allotted finder had started out of its normal position, a circuit was completed for relay 16, extending from grounded battery, winding of relay 16, outer left-hand armature and front contact of relay 17, conductor 66, left-hand armature and front contact of relay 39, left-hand armature and back contact of relay 40 to ground. Relay 16 is energized in this circuit and locks up through its right-hand 40 armature and front contact to conductor 67 and will remain energized until the line is found, since lead 67 is multiplied to the upper right-hand contacts of all sequence switch springs 65 in the A group and all 45 sequence switch springs 62 in the B group. Relay 16, therefore, prevents relay 15 from being again energized until the particular line calling in the main group to which relay 16 is individual, has been found.

50 The energization of relay 39 also opened the circuit for relay 38, and this relay de-energizes and prevents the re-energization of relay 42 to prevent the starting of another finder. The locking circuit for relay 42 was broken when relay 39 was first energized.

With the allotters in the position shown in Fig. 2, if the subscriber at substation 14 desires to initiate a call, the operation of the system is fundamentally similar. In this 60 case, relay 68 would have been energized in series with relay 15 upon the energization of line relay 69. The subsequent energization of relay 17 would then have completed a circuit from grounded battery, winding 65 of relay 70, middle right-hand armature and

front contact of relay 38, which would have been energized as previously described, conductor 71, middle left-hand armature and front contact of relay 17, armature and contact of relay 68 to ground. Relay 70 would 70 have been energized and through its right-hand armature would have supplied ground through allotter brush 32 and its associated contact, over conductor 72, to sequence switch spring 73 and the winding of line 75 relay 74 to grounded battery, to cause the starting of a finder serving the A group, in which the terminals of the calling subscriber's line appear in the lower half of the main group of fifty lines. 80

It is to be observed that, while either of the allotter switches is in operation, that is, while either relay 39 or relay 40 is energized, no finder switch can be started since the circuit for relay 38, which serves to connect through the controlling leads for the start relays 42 and 70 respectively, is open when the left-hand armature of either relay 39 or relay 40 is in its attracted position. Therefore, no finders will be started 90 until both allotters have seized terminals associated with idle finders.

If a second call is originated in the same main group before a line which previously originated a call has been seized, the continued energization of relay 16 will prevent the circuit of relay 15 from being completed. The circuit of relay 17, therefore, cannot be completed and the trip magnet of the group cannot be operated. If a call 100 is originated in some other group while a finder is hunting, it is to be observed that the resultant energization of relay 16, which causes the de-energization of relays 15 and 17, allows the series controlling circuits, 105 which are extensions of conductors 37 and 41 respectively, to be completed to their main groups. Therefore, other main groups may originate calls while a finder is hunting, provided that both the allotters 39 and 110 40 have come to rest in position to allot idle finders.

From the foregoing it is obvious that in one main group only one call can be originated at a time and that any other calls 115 which are originated must wait until a preceding line has been seized. In case a number of calls in the same main group are originated simultaneously or in rapid succession, only one finder will be started and it will seize the line which is lowest in the group. After this finder has come to rest and provided that no other group has taken precedence, the fact that there are still lines in calling condition, as shown by the energization of line relays, will cause another 120 finder to be started as soon as it has been allotted. 125

In case of simultaneous calls in different main groups, the call in the main group 130

containing lines of a lower numerical order will take precedence, since relays 19 and 21 common to such main group will have first access to controlling leads 37 and 41, and therefore the line in the upper group will have to wait until a finder has been started. However, as soon as the finder has been started in search of the line in the lower group, the energization of relay 20 will cause the deenergization of relays 19 and 21, and these relays upon deenergization will connect through the group controlling leads 37 and 41 so that a new finder may at once be started in search of the calling line in the group which is next in precedence, providing that the alloters have taken their positions as previously described. There should be very little delay in the allotment of finders since the allotter is started into operation just as soon as the allotted finder's brush shaft leaves its normal position, as was previously brought out in this description.

The only case in which two finders may be started simultaneously occurs when two lines in different subgroups of the same main group initiate calls simultaneously or in rapid succession. Let it be assumed, for example, that lines 13 and 14 originate calls in rapid succession. If line 13 was the first to originate the call, the operation of the system would be the same as just described and a B finder would be started. If now, substation 14 originates a call before the B finder has moved out of its normal position, that is before relay 39 can become energized, a simultaneous circuit will be completed for relay 70 which will operate to start an A finder. However, since both finders serve the same main group, in each case the second set of brushes will be tripped and both finders will continue in operation until each has seized one of the lines.

It would, of course, be possible to have only one finder out of the entire combined A and B groups idle. In this case the two alloters would both be standing in a position to allot the same finder. In this case, obviously, only one finder would be started and only one line would be seized, but no harm would be done since when the line had been seized and the sequence switch associated with such finder had moved out of position 2, relay 16 would be deenergized and, if meanwhile another finder had become idle, this finder would be allotted and started in the usual manner.

Referring now to the operation as first described, in which case line 13 initiated a call and put into operation the B finder shown in Fig. 1, it is to be observed that when the line associated with substation 13 was found, cut-off relay 34 was energized by means of suitable circuits and caused the deenergization of relay 33. As soon as se-

quence switch 47 moved out of position 2, relay 16 was deenergized. Relays 15 and 36, however, do not again become energized, since ground is now absent at the armature and contact of relay 33. This leaves the subscriber's relays and the subgroup and group relays in their normal condition and ready for reoperation.

It has not been considered necessary to completely disclose the circuits associated with the line finder. It is sufficient to state that when the connection is no longer desired, the restoration of the district or similar selector switch associated with the trunk which terminates in the B finder shown, causes sequence switch 47 to be advanced into position 18.

In position 18 of sequence switch 47 a circuit is completed from grounded battery, winding of down-drive magnet 75, contact of sequence switch spring 76 to ground. The brush shaft is restored to its normal position under the control of magnet 75, and when fully restored a circuit is completed from grounded battery, power magnet of sequence switch 47, upper right-hand contact of sequence switch spring 48, conductor 77, normal commutator segment 78, commutator brush 56 to ground, for moving the sequence switch out of position 18 and into position 1, from which position it may be reallocated for use.

What is claimed is:

1. In a telephone exchange system, calling lines arranged in groups, the lines of each group being arranged in a fixed order, a contact bank comprising a plurality of sections, multiple contact sets in said bank, said lines terminating in said contact sets, a plurality of line finder switches arranged for coöperation with each of said sections, the various groups being so arranged in the various sections that a different group appears as a first choice in each of said sections, and means operative upon the initiation of a call for putting into operation an idle one of the switches which serve a section of said contact bank in which the group containing the contact set of the calling line appears as a first choice.

2. In a telephone exchange system, calling lines arranged in groups, the lines of each group being arranged in a fixed order, a contact bank comprising a plurality of sections, multiple contact sets in said bank, said lines terminating in said contact sets, a plurality of line finder switches arranged for coöperation with each of said sections, the various groups being so arranged in the various sections that a different group appears as a first choice in each of said sections, an allotter switch individual to each of said groups, starting circuits for said line finder switches controlled by said allotter switches, and means operative upon the in-

ition of a call for putting into operation one of the line finder switches which serves a section of said contact bank in which the group containing the contact set of the calling line appears as a first choice, provided that one of such switches is idle.

3. In a telephone exchange system, calling lines arranged in groups, the lines of each group being arranged in a fixed order, a contact bank comprising a plurality of sections, multiple contact sets in said bank, said lines terminating in said contact sets, a plurality of line finder switches arranged for coöperation with each of said sections, the various groups being so arranged in the various sections that a different group appears as a first choice in each of said sections, an allotter switch individual to each of said groups, means operative upon the initiation of a call to start an idle line finder, and means thereupon operative to put into operation the allotter switch which controlled the starting of said line finder to prepare for use an idle finder in the group of finders which serves a section of the contact bank in which the group of lines, to which said allotter is individual, appears as a first choice.

4. In a telephone exchange system, calling lines arranged in groups, the lines of each group being arranged in a fixed order, a contact bank comprising a plurality of sections, multiple contact sets in said bank, said lines terminating in said contact sets, a plurality of line finder switches arranged for coöperation with each of said sections, the various groups being so arranged in the various sections that a different group appears as a first choice in each of said sections, an allotter switch individual to each of said groups, means to start idle line finders as calls are originated, means to operate an allotter switch each time that a line finder is started to prepare for use an idle finder in the group of finders which serves a section of the contact bank in which the group of lines, to which said allotter is individual, appears as a first choice, provided there be an idle finder in such group, and means to prepare for use an idle finder in another group of finders in case all of the finders in the preferred group are busy.

5. In a telephone exchange system, calling lines arranged in groups, the lines of each group being arranged in a fixed order, a contact bank comprising a plurality of sections, multiple contact sets in said bank, said lines terminating in said contact sets, a plurality of line finder switches arranged for coöperation with each of said sections, the various groups being so arranged in the various sections that a different group appears as a first choice in each of said sections, an allotter switch individual to each of said groups, means to successively start

idle line finders under the control of said allotters as calls are originated, and means to maintain said allotters in positions to control the idle finders which respectively serve sections of the contact bank in which the groups of lines, to which said allotters are individual, appear respectively as first choices.

6. In a telephone exchange system, calling lines arranged in groups, the lines of each group being arranged in a fixed order, a contact bank comprising a plurality of sections, multiple contact sets in said bank, said lines terminating in said contact sets, a plurality of line finder switches arranged for coöperation with each of said sections, the various groups being so arranged in the various sections that a different group appears as a first choice in each of said sections, an allotter switch individual to each group, means to operate an allotter switch to control the starting of idle finders in the group of finders which serves the section of the contact bank in which the group of lines, to which said allotter is individual, appears as a first choice, as long as any of these finders are idle, means to prepare for starting line finder switches which serve a subsequent section in case all preferred line finders are busy, and means operative after a line finder in a subsequent group has been started for causing said allotter to pass over idle line finders in subsequent groups and return to its preferred group and allot a line finder therein, provided that, meanwhile, a finder in such preferred group has become idle.

7. In a telephone exchange system, calling lines arranged in groups, each group being divided into a plurality of subgroups, there being a corresponding subgroup in each main group, a set of subgroups comprising such corresponding subgroups, an allotter switch individual to each set of subgroups, a contact bank, comprising a plurality of sections, multiple contact sets in said bank, said lines terminating in said contact sets, a plurality of line finder switches arranged for coöperation with each of said sections, the various subgroups of each main group being so arranged in the various sections that a different subgroup of each main group appears as a first choice in each of said sections, a plurality of multiplied brush sets for each of said line finders, there being as many brushes as there are main groups, and means operative upon the initiation of a call for putting into operation an idle one of the switches which serve a section of said contact bank in which the subgroup, containing the contact set of the calling line, appears as a first choice for the brush set which serves the main group in which said calling line appears.

8. In a telephone exchange system, calling

- lines arranged in groups, the lines of each group being arranged in a fixed order, a contact bank comprising a plurality of sections, multiple contact sets in said bank, 5 said lines terminating in said contact sets, a plurality of line finder switches arranged for coöperation with each of said sections, the various groups being so arranged in the various sections that a different group appears 10 as a first choice in each of said sections, starting circuits for said line finder switches, a plurality of allotter switches, each of said allotter switches being arranged to control the starting circuits of all of said 15 line finder switches, and means operative upon the initiation of a call for putting into operation an idle one of the switches which serve the section of said contact bank in which the group containing the contact set 20 of the calling line appears as a first choice.
9. In a telephone exchange system, calling lines arranged in two groups, the lines of each group being arranged in a fixed order, a contact bank comprising two sections, multiple contact sets in said bank, 25 said lines terminating in said contact sets, a plurality of line finder switches arranged for coöperation with each of said sections, the group of contact sets which appears 30 as a first choice in the first of said sections
- being arranged to appear as a second choice in the second of said sections and vice versa, and means operative upon the initiation of a call for putting into operation an idle one of the switches which serve the section in 35 which the group containing the contact set of the calling line appears as a first choice.
10. In a telephone exchange system, calling lines arranged in two groups, the lines of each group being arranged in a fixed order, a contact bank comprising two sections, multiple contact sets in said bank, said lines terminating in said sections, the group of contact sets which appears as a first choice in the first of said sections being arranged to appear as a second choice in the second of said sections and vice versa, an allotter switch individual to each group, each of said allotter switches being arranged to control the starting of all of said line 40 finder switches, and means operative upon the initiation of a call for putting into operation an idle one of the switches which serve the section in which the group containing the contact set of the calling line 45 appears as a first choice.
11. In a telephone exchange system, calling lines arranged in two groups, the lines of each group being arranged in a fixed order, a contact bank comprising two sections, multiple contact sets in said bank, said lines terminating in said contact sets, a plurality of line finder switches arranged for coöperation with each of said sections, the group of contact sets which appears as a first choice in the first of said sections being arranged to appear as a second choice in the second of said sections and vice versa, an allotter switch individual to each group, each of said allotter switches being arranged to control the starting of all of said line 50 finder switches, and means operative upon the initiation of a call for putting into operation an idle one of the switches which serve the section in which the group containing the contact set of the calling line 55 appears as a first choice.

In witness whereof I hereunto subscribe my name this 30th day of December, A. D. 1919.

SAMUEL B. WILLIAMS, JR.
